United States Patent Office.

LYMAN B. PRINDLE, OF LITCHFIELD, CONNECTICUT.

Letters Patent No. 76,942, dated April 21, 1868.

IMPROVED RAILROAD-RAIL.

The Schedule referred to in these Letters Patent and making part of the same.

TO ALL WHOM IT MAY CONCERN:

Be it known that I, LYMAN B. PRINDLE, of the town of Litchfield, and county of Litchfield, and State of Connecticut, have invented a new and useful Improvement in Continuous or Endless Rails; and I do hereby declare the following to be a full, clear, and exact description of the same, reference being had to the drawing accompanying this specification, and forming a part of the same, and to the figures and letters thereon, in which—

Figure 1 represents a plan view of my improved rail as laid.

Figure 2, a perspective view of the chair to accompany the same.

Figure 3, a vertical cross-section of chair and rail; and

Figure 4, a vertical cross-section of a modified form of chair.

My invention relates to an improvement in the form and construction of rails for roads over which cars are to be run; and it consists in making what is called an endless or continuous rail, together with the chair in which it is supported, in such a form that the rail may be reversed, the under edge being substituted for the upper, when the last shall have become worn so much as to make it necessary, thereby increasing the length of time a rail will last at least to twice that of the ordinary form of rail now in use.

The improvement is equally adapted to rails of either steel or iron, and, when used with the chairs fitted for it, the whole forms a continuous rail of great strength, on which an engine and train of cars may be run without the disagreeable noise and jolting now so common on our railroads, and which tends so greatly to the discomfort of the passengers, and, by the constant jarring, tends to wear out the rail and cars much faster than they would upon a perfect rail.

By the use of my invention, the jolting caused by passing over the joints of the ordinary rail, which, not having near the strength of the other portions, will settle more or less, will be stopped, and thereby the train will run more steadily, require less power, and render every part more durable, as it is well known that there is hardly anything so destructive to the engines and rolling-stock of the cars as this constant jarring and jolting on an uneven rail.

To remedy this, a rail should be capable of retaining its position in a straight line while a train is passing over it, have no yielding joints, and, at the same time, it should be constructed so as to be readily and easily repaired when necessary.

To accomplish this is the object of my invention, and in order that others may understand its construction and operation, I will particularly describe it.

A A, fig. 1, represent the two halves of my rail in position, as when laid for use, and the same are shown in section at fig. 3. These halves are made exactly one like the other, and, as seen in fig. 3, are wider at one edge than the other. When put together, the narrow edge of one half is put upwards, and the wide edge of the other, so that they form together a rail nearly square in section, having the two opposite corners slightly rounded off. On the two sides of the rail, a groove, *a*, fig. 3, is cut, which receives the key *b*, of wood or iron, or a corresponding projection on the inner face of the chair, (fig. 4,) by either of which it is held in its place. The rails are so placed in the chairs that the upper rounded corners are on the inside, and on this inner portion of the rail the car-wheels run. The chairs, B B, in which the rail is secured, are shown in figs. 2, 3, and 4. They are made of iron, cast in the shape represented, and are secured to the ties by spikes in the ordinary manner. From the base of the chair arise two lugs, C and D, the inner faces being at right angles with the base of the chair, and at such distance apart as to receive the rail between them. That part of the chair which lies against the outer part of the rail (as at *C*) is made of a height about equal to the depth of the rail, so that when the rail is placed in the chair, the two will be of the same height, as shown at fig. 3. The other lug, *D*, is only about one half the height of *C*, as much less strain comes upon that, and it only need be of height and strength as will serve to retain the rail in its seat in the chair. On the inner face of the lug *C*, a groove, *e*, is cut or cast, as shown in fig. 2, at the same height from the seat of the chair as the corresponding groove in the

rail is, and in the cavity thus formed a key, *b*, of wood or iron, is driven, by which the rail is retained very firmly in its seat. If desired, in the place of the groove *c*, a corresponding projection may be cast, (see fig. 4,) which will fit into the groove of the rail, and then the key *b* may be dispensed with. In laying the rails, a chair is placed at each joint, or where the two ends of the half rails come in contact, and when the key is driven in its place, or the key being dispensed with, the projection on the inner face of the lug *C*, in the groove of the rail, a very strong joint is formed, so that there is of the two parts a continuous rail formed, of sufficient strength to bear any ordinary weight, without bending or yielding in the least.

This compound rail, having its top and bottom edges similar, is capable of being reversed, when the upper edge shall have become worn, and, when the key is used, these repairs may be made quickly and easily, without disturbing the chair, as, by simply driving out the key, the rail may be lifted from its seat in the chair, and a single length can be taken out at any time, and another substituted in its place, without disturbing any other portion of the rails, thus greatly facilitating the making of the necessary repairs, and lessening the expense of the same—a great desideratum, and one, it is believed, not attained before in any form of continuous rail known.

Having thus described the construction and operation of my invention, what I claim as new, is—

A continuous reversible rail, with its accompanying chair and key, constructed substantially as herein set forth and described.

In testimony whereof, I hereunto subscribe my name in the presence of—

LYMAN B. PRINDLE.
